UNITED STATES PATENT OFFICE.

JOHN WENZEL, OF NEW YORK, N. Y.

DUMPING-WAGON.

1,096,083.

Specification of Letters Patent. Patented May 12, 1914.

Application filed February 27, 1913. Serial No. 751,080.

To all whom it may concern:

Be it known that I, JOHN WENZEL, subject of the King of Hungary, residing at 235 West Sixty-fifth street, New York, in the 5 county of New York and State of New York, have invented certain new and useful Improvements in Dumping-Wagons, of which the following is a specification.

This invention relates to unloading machinery and has special reference to devices 10 for unloading vehicles of the coal wagon type.

The principal object of the invention is to provide an improved and simplified mechanism 15 of the type described and for the purpose specified.

The second object of the invention is to provide improved means for elevating the front of a wagon body while the rear thereof 20 of remains supported by the frame.

A third object of the invention is to provide improved means for elevating the body, after angular adjustment with relation to the frame while at the same time retaining 25 such angular adjustment.

A fourth object of the invention is to provide improved means for returning the body to normal position after unloading.

A fifth object of the invention is to provide 30 improved means for regulating and controlling the downward movement of the body.

With the above and other objects in view the invention consists in general of certain 35 novel details of construction and combination of parts hereinafter fully described, illustrated in the accompanying drawings, and specifically claimed.

In the accompanying drawings, like characters 40 of reference indicate like parts in the several views, and;

Figure 1 is a side elevation showing the frame and a portion of the body with the latter in raised position. Fig. 2 is a partial plan with the body removed and showing the parts when the body is lowered. Fig. 3 is a front elevation of the body and frame, the former being in partly raised position. Fig. 4 is a longitudinal section on line 4—4 of Fig. 3 showing the body raised. Fig. 5 is a similar view showing the body lowered. Fig. 6 is a perspective of the bars which support the body when raised. Fig. 7 is a detail elevation of the rear end bar 55 arrangement. Fig. 8 is a detail section showing the chain anchor or lock. Fig. 9

is a detail of the controlling brake. Fig. 10 is a perspective of one of the bearings for the supporting bar journals. Fig. 11 is a detail perspective of a certain trip used here- 60 with.

In carrying out this invention there is provided a main wagon frame 1 upon which are mounted cross bars 2 and extending longitudinally from one of these bars 1 to the other are beams 3. Fastened to the inner sides of the beams 3 at the lower edges thereof are angle iron roller tracks 4. Secured to the under side of each beam 3 is a bearing 7 and in these bearings, is journaled a shaft 8 whereon is fixed a gear 9 which meshes with a pinion 10 mounted on a stub shaft 11 and connected to a gear 11. This gear 11 meshes with a pinion 12 fixed on a stub shaft, the latter being provided with a 70 squared end 13^a so that a crank may be applied thereto and thus move the entire gear chain. In order to support the outer ends of these stub shafts the beam 3 has secured thereto a plate 14 in which the inner ends 80 of the stub shafts are journaled and this plate has secured thereto a D-bar 15 in which the outer ends of said stub shafts are journaled. On the last mentioned beam 3 is provided a pivot pin 17 whereon is mounted 85 a pawl 16, the end of said pawl engaging the teeth of the pinion 12 to prevent back motion of the gearing. This pin 17 also serves the purpose of securing one end of a brake band 19 which passes around 90 a brake drum 18 revolving with the pinion 12 and preferably integral therewith. The other end of this brake band 19 is attached to a brake lever 20 suitably pivoted on the beam 3.

Secured to the shaft 8 and wound thereon are chains 21 which have their free ends connected to V-shaped links 22, the latter being connected by straps 23 to a shaft 24. This shaft 24 is provided at its ends with 100 rollers 25 which move upon the tracks 4. Upon this shaft are also pivoted the ends of certain bars 26 which have their opposite ends pivoted, as at 27, to the body 28. On the rear cross bar 2 are mounted pivot supports 30 in which is pivoted one end of a bar 29, the remaining end being pivoted to a pivot or joint 27. Pivoted to the body 28 at 31 are bars 32 which have their opposite ends revolvably mounted on a shaft 33 carrying rollers 34 which roll along the bars 4. This shaft 33 passes through the slots 37 of

yokes 36 which are connected by reach rods 35 revolvably mounted on the shaft 24. Pivoted to each of the bars 35 is a dog or latch 38 and on each of these dogs is a catch 39 which is arranged to contact with a trip 5 secured to the respective beam 3.

In order to hold the body against displacement by jolting there are provided manually releasable hooks 40 which are arranged to 10 engage pins 6 on the beams 3 when the body is lowered.

The operation is as follows: The shaft 8 is rotated by turning the crank and the chains 21 draw the shaft 24 rearwardly. 15 Owing to the fact that the rear ends of bars 29 are stationary the point 27, when acted upon by the bar 26 must move upwardly carrying with it the body-frame 28, and at the same time slotted bar 35 is moving 20 rearwardly, causing the beveled rear ends of the dogs 38 to ride upon the shaft 33; at the exact moment when the front ends of slots 37 come in contact with shaft 33, the dogs 38 drop over it for a purpose 25 to be mentioned later, and until this moment, the angle of adjustment has been steadily increased, the rear end of the body-frame remaining resting upon the rear end of the main frame, but after the front ends 30 of the slots come in contact with the shaft 33, the said shaft is pushed rearwardly, and the bars 32 carry the body-frame in the same direction, at the same time carrying the body upwardly thereby equalizing the tendency 35 of bars 26 to change the angle of adjustment. When the dog or pawl 16 is released the pressure due to weight of the body carries the rollers 25 forward, and as the bars 35 are on the same shaft with rollers 40 25, the shaft 33 is also drawn forward by reason of the engagement with said shaft of dogs 38. The catch 39 rides over trip 5 and lifts the dog 38 from shaft 33 at the moment the rear end of the body-frame 45 touches the main frame thus allowing the slotted bars 35 free movement forwardly, the transversely bent ends of catches 39 falling upon the top edges of elongated portion 36 and limiting the downward movement of 50 dogs 38.

Having thus described the invention, what is claimed as new, is:—

1. The combination with a vehicle frame; of a body frame, links each having one end 55 pivoted to the vehicle frame and the other end pivoted to said body frame, other links arranged in pairs and each having one end

pivoted to the body frame and the other end movable longitudinally of the vehicle frame, means to first move one pair of said links 60 and then both pairs thereof, and pivoted hook members for locking the longitudinal movable ends of said links together.

2. The combination with a vehicle frame; of a body frame, links each having one end 65 pivoted to the body frame and the other end pivoted to the vehicle frame, tracks carried by the vehicle frame, a pair of links each having one end pivoted to the body frame, the other end of each of the last mentioned 70 links being provided with a roller resting on said track, a second pair of links arranged similarly to the last mentioned pair, shafts connecting the roller of each pair of links, yoke bars pivoted to the forward shaft and having slotted ends engaging around the rear shaft, chains connected to the forward shaft and extending rearwardly, a winding drum around which the free ends of said 75 chains are wound, and means to releasably hold the rear shaft in the forward ends of the yoke bar slots.

3. The combination with a vehicle frame; of a body frame, links each having one end 80 pivoted to the body frame and the other end pivoted to the vehicle frame, tracks carried by the vehicle frame, a pair of links each having one end pivoted to the body frame, the other end of each of the last mentioned links being provided with a roller resting 85 on said track, a second pair of links arranged similarly to the last mentioned pair, shafts connecting the roller of each pair of links, yoke bars pivoted to the forward shaft and having slotted ends engaging around the rear shaft, chains connected to the forward shaft and extending rearwardly, a winding drum around which the free ends of 90 said chains are wound, and means to releasably hold the rear shaft in the forward ends of the yoke bar slots, said means comprising a pair of latches carried by the yoke bars and arranged to engage the rear shaft when the yoke bars are moved rearwardly, arms fixed relative to said latch, and releasable cams carried by the vehicle frame and adapted to engage said arms and lift the latches as the yoke bars move forwardly.

In testimony whereof I affix my signature in presence of two witnesses.

JOHN WENZEL.
